UNITED STATES PATENT OFFICE.

THEODORE A. HAMMOND, OF PASSAIC, NEW JERSEY.

CONNECTOR.

940,012.

Specification of Letters Patent. Patented Nov. 16, 1909.

Application filed March 18, 1908. Serial No. 421,847.

To all whom it may concern:

Be it known that I, THEODORE A. HAMMOND, a citizen of the United States, and resident of and whose post-office address is 5 170 Bloomfield avenue, in the city and county of Passaic, State of New Jersey, have invented certain new and useful Improvements in Connectors, of which the following is a specification.

10 My invention particularly relates to improvements in terminal connectors adapted for use on batteries and similar articles or devices where a simple positive and easily removable connection is desirable.

15 In carrying my invention into practice, I dispose of the ordinary binding nuts now commonly employed on dry cells for retaining the conductor in place around and in contact with the screw post, as these nuts 20 are liable to and often do work loose, especially when subjected to the vibratory movement caused by the running of an automobile, etc., resulting in a loose connection and often in an interruption in the ignition 25 circuit.

My terminal connector is used in the stead or place of the binding nuts heretofore used, and affords a tight connection that cannot be vibrated loose.

30 Referring to the accompanying drawing in which like reference numerals indicate like parts throughout—Figure I represents a complete connector comprising two terminals of my improved construction linked 35 together with a suitable conducting wire. Fig. II is a view of a portion of a dry battery showing one of its binding posts equipped with my improved terminal. Fig. III is a view illustrating the stamping or 40 blank from which my improved terminal is formed.

In the figures, —1— represents a conducting wire having a terminal connector at either end. The terminal is made of suitable 45 springy material, and is struck up or formed from the shape of blank illustrated by Fig.

III, and, when formed, comprises a bow or U-shaped shank portion —2—, perforated projecting or gripping portions —3— (four in number), and the sleeve portion —4—. 50 The perforated projecting portions at both sides of the shank portion —2— are adapted to align with one another so as to permit the screw or binding post to pass through them, so that the edges of the perforated 55 projections —3— will seat or catch in the screw threads of the post —5—, as shown in Fig. II. A pair of longitudinally spaced openings 7 are punched in the blank toward that end thereof at which the sleeve 4 is 60 formed, and the conductor 1 is secured to the terminal by passing the end 6 of the wire thereof first through the opening 7 farthest from the sleeve and then back through the other opening 7, the extremity of the wire 65 and the end portion of the conductor being clamped within the sleeve.

Having thus described my invention, what I claim as new herein, and desire to secure by Letters Patent is:—

The herein described terminal connector for connecting an electrical conductor to a post, the said terminal connector being formed from a single blank of sheet material and comprising a central shank extending 75 longitudinally of the conductor and provided at one extremity with a sleeve for engaging the conductor, the two end portions of the shank being each provided with a pair of oppositely disposed perforated gripping 80 members which extend in parallel planes from the edges of the shank, the perforations of one set of gripping members being adapted to register with the perforations of the opposite set of gripping members to receive the post and the resiliency of the shank then holding the said gripping members in engagement with the post.

THEODORE A. HAMMOND.
